(No Model.)

E. D. DOUGHERTY.

GRIP FOR CABLE RAILWAYS.

No. 351,254.

Patented Oct. 19, 1886.

UNITED STATES PATENT OFFICE.

EDWARD DYER DOUGHERTY, OF PHILADELPHIA, PENNSYLVANIA.

GRIP FOR CABLE RAILWAYS.

SPECIFICATION forming part of Letters Patent No. 351,254, dated October 19, 1886.

Application filed July 6, 1886. Serial No. 207,231. (No model.)

To all whom it may concern:

Be it known that I, EDWARD DYER DOUGHERTY, of Philadelphia, in the county of Philadelphia and State of Pennsylvania, have invented certain new and useful Improvements 5 in Grips for Cable Railways; and I do hereby declare the following to be a full, clear, and exact description of the invention, such as will enable others skilled in the art to which it applies to make and use the same.

My invention relates to an improvement in grips for cable railways, and more particularly to the grip shown and described in my pending application filed May 17, 1886, and numbered 15 202,437.

The object is to provide an improved construction of parts for permitting the rollers to gradually recede until the cable is gripped by a pair of metallic-faced jaws; and with this end in view my invention consists in the parts 25 and combinations of parts, as will be more fully described, and pointed out in the claims.

In the accompanying drawings, Figure 1 is a view of the lower section of a grip, partly in 25 section and partly in elevation. Fig. 2 is a side view of the same; and Fig. 3 is a view in section, showing the manner of connecting the levers to the spring.

A represents a depending support or hanger, 30 to which the grip mechanism is attached.

To one side of the hanger A is secured a flat plate, B, bent outwardly, downwardly, and inwardly at the lower edge, forming in cross-section three sides of a rectangular loop, as shown at b, b', and b''. At or near the opposite ends of the loop portion of the plate B are formed elongated slots b³, in which the boxes C, carrying the rollers C', slide or move. These rollers C' are provided with reduced ends or 35 trunnions, or with bolts passing through the rollers, which fit snugly in the boxes C, and when the rollers are in their normal positions the boxes rest against the inner boundaries of the slots. In the outer face of the portion b' 40 of the plate B, and preferably at or near the center thereof, is formed a socket, D, for the reception of a spiral spring, D', which latter, through the medium of the levers E and pins E', hold the boxes C in contact with the inner 45 walls of the elongated slots. The levers E, four in number, are pivoted, respectively, to the lugs e, integral with or attached to the rear 50

face of the plate B, with their longer arms resting on the washer f, secured on the spring D', and their shorter arms in contact with the outer 55 ends of the pins E', which latter pass through openings in the section b' of the plate and bear against the boxes C, carrying the rollers C'. Within the socket D, behind the spring D', is the disk or nut D², which latter is prevented 60 from turning, and is provided centrally with a screw-threaded opening for the passage of the adjusting screw F, the inner end of which bears against the base of the socket. Located within the coils of the spring D', and resting on the 65 disk D², is the tube g, the upper end of which is above the levers. By turning the screw F the disk is moved up or down and the spring compressed or relaxed, and the tension on the rollers increased or diminished. 70

h is a nut for locking the parts in position after the spring has been adjusted.

Between the rollers C', and secured to the plate B, is a bearing plate or block of soft metal, E², conveniently held in position by 75 screws passing through the portion b' of the plate B, as shown in my pending application, No. 202,437. The faces of the rollers C' project slightly beyond the face of the block or plate E² and the plate B, and the plate B, with 80 its attachments, as described, and the strengthening rib or web e', form what may be properly termed the "stationary jaw" of the grip.

To the opposite side of the hanger A is secured a plate, F', provided at or near its lower 85 edge with a pair of perforated lugs, to which are hinged the upwardly-extending arms g' of the swinging jaw G. The lower portion of the jaw G is shaped quite similarly to the parts b, b', and b'' of the jaw B, and has in its ends a 90 pair of upright rollers secured thereto in the same manner as and opposite to the rollers C'. This jaw G is also provided with a soft-metal gripping-plate, I, similar to the ones shown and described in the application above referred 95 to, and located opposite the plate E in the jaw B. At the lower end of the jaw G, one at each corner, are secured horizontal slightly-tapered rollers K, which occupy positions transversely to the line of the cable, and are adapted to 100 support it between the gripping-faces of the jaws, and to release and pick it up as the jaw is swung outwardly and inwardly on its hinges.

A laterally and downwardly extending bi-

furcated arm, I, is secured to the upper portion of the plate F', and in the ends of its branches is secured the bolt M, on which the eccentric or cam wheel N is mounted. The wheel N is adapted as it rotates on its support to allow the jaw G to swing outwardly or to force the same inwardly, according as its bulging side is swung away from or toward the back of the jaw. The pitman and lever for operating the wheel are not shown, but is conveniently connected with the wheel at the point n, and may be of any well-known or approved construction. The jaw G is caused to have a tendency to swing away from the jaw B by a counter-weight, O, secured to the upper end of one of the arms g', so that its depression will tend to swing the jaw outwardly.

As the cable is grasped between the jaws, the upright rollers first come in contact with it and form a partial hold, perhaps giving the car its first impulse, and in any event preventing the cable from chafing against the soft-metal plates as it approaches its surface, and when the jaws are firmly brought together the said rollers readily yield and allow the metal plates to grasp the cable firmly.

I make no claim in this application to the manner of locking the jaws together, nor to the counter-balance for opening the movable jaw, as these parts are shown, described, and claimed in my application above referred to.

Having fully described my invention, what I claim as new, and desire to secure by Letters Patent, is—

1. In a grip for cable railways, the combination, with a jaw, of one or more movable bearings secured in said jaw, and a single spring for exerting a yielding pressure against the opposite ends of the movable bearing or bearings, substantially as set forth. 35

2. In a grip for cable railways, the combination, with a jaw, of one or more movable bearings secured in said jaw, a single spring for exerting a yielding pressure against the opposite ends of the movable bearing or bearings, 45 and a screw for increasing or diminishing the tension of the spring, substantially as set forth.

3. In a grip for cable railways, the combination, with a jaw, of two movable bearings secured to said jaw, a single spring for exerting a yielding pressure against the opposite ends of said bearings, and a stationary bearing located between the movable bearings, substantially as set forth. 50

4. In a grip for cable railways, the combination, with a jaw and two movable or sliding rollers journaled therein, of the levers exerting a pressure against the ends of the rollers, and a spring bearing against the levers, substantially as set forth. 55

In testimony whereof I have signed this specification in the presence of two subscribing witnesses.

EDWARD DYER DOUGHERTY.
